D432,142 S 10/2000 Olson et al.

The design relates to a body panel for an agricultural vehicle, for example, a baler for bailing material, such as agricultural crop material. The body panel comprises a major side panel with narrow front, rear, top and bottom panels extending from the major side panel. The major side panel is slightly curved outwardly when viewed from the front and from the top, and includes an inwardly recessed panel extending over the upward portion of the major side panel.
